UNITED STATES PATENT OFFICE.

SAMUEL L. EASTBURN AND ROBERT C. REEVES, JR., OF SLOATSBURG, NEW YORK.

CLOSET-SEAT.

No. 904,053.

Specification of Letters Patent. Patented Nov. 17, 1908.

Application filed November 4, 1907. Serial No. 400,523.

To all whom it may concern:

Be it known that we, SAMUEL L. EASTBURN and ROBERT C. REEVES, Jr., citizens of the United States, and residents of Sloatsburg, in the county of Rockland and State of New York, have made and invented certain new and useful Improvements in Closet Seats, of which the following is a specification.

Our invention relates to an improvement in water-closet seats, and has for its object to provide a device adapted for use or employment with an ordinary closet seat, and comprises in part a supplemental seat having a relatively small opening therein for convenient use by a child, and which may be substituted, used or employed in lieu of the lid now ordinarily employed with the usual seat, the ordinary lid being first detached from the hinge and our present device secured by said hinge in the place thereof.

The further object of our invention is to so construct the device that it may be neatly and compactly folded, whereby to conveniently carry the same when traveling, which shall be neat in appearance, cheap to manufacture and so constructed and arranged as to obviate all danger of a child from accidentally falling therefrom.

With these and other ends in view, our invention consists in certain novel features of construction and combinations of parts, as will be hereinafter fully described and pointed out in the claims.

In the accompanying drawings Figure 1 is a perspective view of our improved device, the supplemental seat being in its lowered position. Fig. 2 is a longitudinal sectional view of the device in its closed position, and Fig. 3 is a sectional view taken on the line 3—3 of Fig. 2. Fig. 4 is a detached sectional view of a modification.

Referring to the drawings, 4 indicates a bowl of any suitable construction, to which the usual or main seat 5 is hinged in any suitable manner, said seat being provided on its under side with the usual rubber lug 6, adapted to rest upon the upper edge of the bowl. Supported upon the closet, preferably by suitable hinges 8, is our improved device, which comprises a supplemental seat 9, adapted to be superimposed upon the main seat 5, and which is provided with a comparatively small opening 10, said seat being

provided on its under side with lugs 11, of rubber, or other suitable material, whereby any marring or scratching of the upper surface of the seat 5 is prevented, when the device is in its lowered position. At its rear side, the supplemental seat is provided with a thickened, laterally extending portion 12, having its upper, outer edge beveled as indicated at 13. This thickened portion may be formed integral with the supplemental seat, or it may be made separate and securely fastened thereto in any suitable manner.

Hinged to the outer edge of the portion 12, by suitable hinges 15, is the cover or lid 14, the under side of which is provided with a recess 17, extending throughout practically the entire area of the cover, as shown in Fig. 1, for the purpose hereinafter described. The upper surface of the cover is preferably flush with the upper surface of the portion 12, and its rear edge is beveled, as indicated at 16, said beveled edge co-acting with and abutting against the beveled edge 13, when the cover is raised in the position shown in Fig. 1. At its front edge 18 the cover is provided with a spring catch 18 of any suitable construction, which is adapted to normally lock the cover to the supplemental seat, whereby they may be raised simultaneously to expose the usual seat 5, as indicated by dotted lines in Fig. 2, but which may be pressed or operated to unlock the parts when it is desired to raise only the cover, and expose the supplemental seat 9, as shown in Fig. 1.

Hinged, or otherwise movably secured to the upper surface of the supplemental seat 9, and adjacent the sides thereof, are the arms or sides 19, shaped to conform with the recess 17 in the cover 14, which are normally folded or turned inward, as shown in Figs. 2 and 3, in which position they are entirely inclosed in said recess, but which are rotated or turned upward when the supplemental seat is to be used, as shown in Fig. 1, in which position their inner edges will abut against the inner wall of the recess 17, the arms being retained in this position by means of suitable clips 20, the clips shown being pivoted at their inner ends, whereby they may be evolved into operative or inoperative position as desired. By thus arranging the parts, the lid 14 and arms or sides 19 are held or supported in their upright or opened positions and thereby assist in pre-

venting the child from accidentally falling from the seat.

To strengthen and assist in supporting the sides or arms 19 in place, and in order to 5 completely inclose the child and prevent it from accidentally falling from or climbing out of the device, we detachably secure to the sides 19 in any desirable way or manner, a suitable table or tray 22, that in the drawings being shown as fitted in the slots or 10 openings 21, formed in the forward ends of the arms or sides 19, and there detachably held by the bolts or catches 23.

While we prefer to form the device of 15 wood, it will of course be understood that it may be made of other material, as, for instance, the several parts may be shaped or stamped up from metal or may be made from hard rubber, papier-mâché, etc.

20 As shown in Fig. 4, the flange 24 formed on the lid 14 may be made sufficiently large in order to inclose and conceal not only the arms or sides 19, but also the peripheral edge of the supplemental seat 9, so that when the 25 device is folded and lowered on to the main seat, it will have every appearance and semblance of the usual lid.

From the foregoing it will be seen that our improved device is so designed that it 30 may be readily substituted for the usual lid, being hinged to the ordinary seat by the same hinges, after said usual lid has been detached; that when closed or folded it has all the appearances of the usual lid, it being 35 made of about the same size and material and of about the same thickness, the several parts being held in their closed or folded adjustment by catches, enabling it to be raised or lowered as in the case of the ordinary lid; that when traveling it may be 40 easily and readily detached from the closet seat, and as it folds in a flat, compact form, it may be conveniently carried in a valise or suit case.

45 Having described our invention, what we claim as new, and desire to secure by Letters Patent, is:—

1. A lid adapted for use with an ordinary closet seat, said lid comprising a supplemental seat, a cover hinged to the rear side thereof, said cover being provided with a downwardly extending continuous peripheral flange around the front and sides thereof, and sides hinged to said supplemental 50 seat and adapted to be folded downwardly and completely hidden by the flange on said cover when the latter is folded downwardly on said seat, the whole being constructed and arranged to form a lid for the ordinary 55 seat substantially as described.

2. A lid adapted for use with an ordinary closet seat, said lid comprising a supplemental seat, a hinged cover for the supple-

mental seat, said cover having a downwardly extending peripheral flange around its front 65 and sides and inclosing a recess, independent sides hinged along their outer edges to the supplemental seat and opening away from each other, said sides, when folded on the supplemental seat and the cover lowered 70 thereon, adapted to be received into the recess of said cover and to be hidden from view by the peripheral flange thereof, and engageable devices between the free ends of the lid and the supplemental seat whereby 75 the two are locked together in compact form.

3. A lid adapted for use with an ordinary closet seat, said lid comprising a supplemental seat, a hinged cover for the supplemental seat, said cover having a downwardly 80 extending peripheral flange around its front and sides and inclosing a recess, independent sides hinged along their outer edges to the supplemental seat and opening away from each other, said sides, when folded on 85 the supplemental seat and the cover lowered thereon, adapted to be received into the recess of said cover and to be hidden from view by the peripheral flange thereof, and engageable devices between the free ends of 90 the lid and the supplemental seat whereby the two are locked together in compact form, said devices including a catch on one of the parts and a latch on the other part engaged thereby.

4. A lid adapted for use with an ordinary closet seat, said lid comprising a supplemental seat, a cover therefor, said cover being hinged at the back and having a peripheral flange extending around the sides and 100 front and bounding an intermediate recess, and independent sides hinged along their outer edges to the supplemental seat and adapted to fold inwardly thereon and to occupy an area which substantially corresponds to the area of the recess in the cover, whereby when said cover is folded down on the supplemental seat it houses the sides and the peripheral flange of the cover extends over the edges of said sides and conceals 105 them from view.

5. A lid adapted for use with an ordinary closet seat, said lid comprising a supplemental seat, a cover therefor, said cover being hinged at the back and having a peripheral flange extending around the sides and front and bounding an intermediate recess, outer edges to the supplemental seat and 115 independent sides hinged along their adapted to fold inwardly thereon and to 120 occupy an area which substantially corresponds to the area of the recess in the cover, whereby when said cover is folded down on the supplemental seat it houses the sides and the peripheral flange of the cover extends 125 over the edges of said sides and conceals

them from view, and means for locking the cover to the supplemental seat and permitting this seat and the cover and its contained sides to be raised and lowered relative to a main seat.

Signed at New York borough of Manhattan in the county of New York and State of

New York this 31st day of October A. D. 1907.
